PRESS BRAKE DRIVE

James B. Castle, Oakland, Calif., assignor to Reconstruction Finance Corporation, San Francisco, Calif., a corporation of the United States

Application August 29, 1945, Serial No. 613,345

2 Claims. (Cl. 74—110)

1

This invention relates to sheet metal bending brakes of the heavier type for relatively thick metal bending and forming generally termed "press brakes" and the principal object of the present invention is to provide a novel, simple, effective hydraulic operating device or "drive" for operating the movable jaw of the brake.

Advantages and special features of the invention will appear in the following description and accompanying drawings.

In the drawings:

Fig. 1 is a front view elevation of a conventional press brake fitted with my improved "drive" or operator.

Fig. 2 is a rear elevation of the press showing the hydraulic power actuating cylinder.

Fig. 3 is a vertical section taken along the line 3—3 of Fig. 1.

Fig. 4 is a view similar to that of Fig. 2 but in reduced scale broken centrally along a vertical line, and showing the use of two power cylinders instead of but one.

Fig. 5 is a detail view showing a modified form of adjustable connection from the hydraulic cylinder piston to the lever arm of the press.

Fig. 6 is an end view of Fig. 5.

In further detail the drawings show at 1 the lower front wall or fixed jaw of the brake press, 2 the two vertical side walls, 3 the upper or vertically movable wall or jaw of the press suitably guided as at 4 to move up and down above wall 1 to force a metal plate against or over any desired form of die supported along the upper edge of fixed wall 1, such as the special die bar of cross section indicated in position at 5, but which of course may take any form depending on the nature of the bending work being done.

Adjustably secured to slots 6 in wall 1 is a shelf or table 7 for supporting the "work" or plate being bent and which may be fitted with one or more screw clamps 8 for holding the work to the table. Bolts 9 serve for holding the table at any desired height, and open gaps 10 in the side walls 2 provide for long plates or bars being worked on which extend beyond the side walls 2 of the press. Preferably, suitable floor strips 48 are welded to the lower ends of side plates 2.

Extending between both side walls adjacent the top of the same is a relatively heavy shaft 14 revolvably supported at both ends in bearings 15, while secured to the shaft as by keying or welding are a pair of operating levers 16, 16, one adjacent each side wall 2. These levers extend substantially horizontally with their short ends or arms 16' extending forward in overhanging relation

2

to the movable press jaw 3 and each pivotally connected thereto as by links 17 pivoted at 18 to the lever end and at 19 to a lug 20 welded to the movable jaw 3. It is of course evident that while I show the long operating levers 16 with the short levers 16' formed in one piece, this is not necessarily so.

The rear or long ends or arms of the operating levers 16' are provided with a series of spaced yokes 21, 22, 23, 24 welded along the lower edge of the lever and each formed with aligned holes 25 to selectively receive the bolt pin 26 for pivotally connecting to a socket 27 formed on the outer end of a transversely extending yoke 28 in turn connected to a piston rod 29 of a hydraulic power cylinder 30.

Piston rod 29 extends through a suitable stuffing box 30' and is provided with a piston 31 secured to it within the cylinder. The cylinder is pivotally mounted on a pin 32 between a pair of spaced lugs 33 welded to a pair of downwardly diverging plates 34 which extend horizontally between the side walls 2 and are welded or otherwise secured thereto.

It should be noted that in the open position of the press jaws in Fig. 3 the centers of the yoke holes 21—25 all substantially fall on a common arc 35 so that whichever yoke is connected to the power piston rod will not materially change the press opening. Also that the lower edge of the long lever arms 16' is curved substantially concentric with arc 35.

The hydraulic power piston is indicated as double acting and for the pressure liquid to be alternately forced into and discharged from suitable hose connections 36, 37 at opposite ends of the cylinder, from a pump or other source of liquid pressure under control of suitable valves for starting, stopping, and reversing the piston all as well-known in the hydraulic press art and not shown herein as forming no part of the invention claimed.

In Fig. 2 the yoke 28 which transmits the piston force to the two press levers is indicated as of thick steel plate rigidly welded to both sockets 27 and is also formed with a socket 28' in which the upper end of the piston rod is rigidly secured as by welding or otherwise.

In the arrangement shown in Fig. 4 two power cylinders are used instead of the one cylinder shown in Figs. 2 and 3, and they are numbered 40, 41 and their piston rods 29' are individually pivotally connected by pins 26' directly to the ends of press levers 16, and the hydraulic power

cylinders are operated simultaneously by suitable hydraulic connections not shown.

Instead of the spaced yokes 27 for variously connecting the piston rod to the press levers to vary the stroke, speed, and power, the modified construction shown in Figs. 5 and 6 may be used and wherein the long end 16" of one of the levers is shown formed with an arcuate groove 44 on both sides, and the connecting yokes (21-24) give way to an H-shaped bracket 45 provided with aligned holes 25 in its lower legs to receive a pin (as shown in Fig. 4 at 26' for connecting to piston rod 29'), while its upper legs are formed with confronting edges 46 engaging the grooves 44 for sliding to any position along the lever desired. The bracket is locked at any desired point as by one or more set screws 47 or any other suitable means.

Other features shown in the drawing, common to such press brakes and not concerned with the present claims, include a removable working edge 3' on the jaw to permit various forms and size of working edges to be used are well-known and not concerned with the present invention.

In considering my improved press brake operating apparatus above described, it will be noted that in the construction shown in Fig. 4 one of the power cylinders may be omitted and if shaft 14 is large and rigid enough the operating force will be transmitted from one lever 16 through the shaft 14 to the other so that the pressure exerted throughout the length of the press jaw will be uniform, and hence the long end of the lever not connected to a power cylinder piston may be omitted. Also that similarly where but one long lever is connected to a power cylinder piston the long lever could be in the center of the shaft 16 to thereby equalize the twisting effort or torque induced in the shaft.

Also to be noted is that while I show and prefer the power cylinder to be pivotally mounted on the press structure and the piston rod pivotally connected to the press lever, these connections may be reversed as well as understood in piston-cylinder devices as being the equivalent of the connections shown.

Having thus described my improved press brake

operating apparatus and the manner of its operation, what I claim is:

1. In a press brake having a frame including a pair of spaced side walls and a vertically movable press jaw extending transversely of the press at the forward edges of said walls, the improvement which comprises an overhead shaft extending across between said walls and provided with bearing support on said walls, a pair of levers spacedly mounted on said shaft each having a short and a long arm, the short arms extending over said movable jaw, link connections between the short arms and the movable jaw for raising and lowering the jaw as the arms are operated, the long arms extending overhead rearwardly of the press, a transversely extending rigid yoke pivotally connected at its ends respectively to said long arms, an upwardly extending double-acting hydraulic power cylinder positioned at the rear of the press with a piston rod at its upper end, said piston rod rigidly secured at its end to a central point on said yoke, a transversely extending frame member on the press structure rigidly connecting its side walls, and means pivotally connecting the lower end of said cylinder to said frame member.

2. In a structure as set out in claim 1, said long lever arms provided with a plurality of selective pivot connections for said yoke spaced along the arms and arranged substantially on an arc struck from the pivotal axis mounting of said power cylinder.

JAMES B. CASTLE.
